UNITED STATES PATENT OFFICE

HARRY AUST, OF PHILADELPHIA, PENNSYLVANIA

MULTIPLE TOE HOSE

Application filed October 19, 1928. Serial No. 313,554.

This invention relates to hosiery for ladies and men and more particularly to a hose having a double toe.

The purpose of the invention is to provide 5 a hose having two toes, an inner toe and an outer toe, so that when one of the toes has worn through it may be cut off allowing the other toe to be used.

This construction of double toe is particularly adapted for use in connection with 10 seamless hosiery, a product constructed on circular or seamless hose knitting machines.

Another purpose is to provide a double toe hose, wherein the inner toe section may 15 be made of a different material from the outer section, for example of heavier material, so as to withstand the wear, though it is understood both toe sections may be made of the same material.

20 It is to be understood that the particulars herein given are in no way limitative, and that while still keeping within the scope of the invention, any desired modification of details and proportions may be made in 25 the construction of the appliance according to circumstances.

The invention comprises further features and combination of parts to be hereinafter set forth, shown in the drawings and 30 claimed.

In the drawings:—

Figure 1 is a view of a hose showing the two toe sections partly attached to the body of the foot of the hose.

35 Figure 2 is a view showing the inner toe section connected completely to the body of the foot of the hose with the outer toe section partly disconnected.

Figure 3 is a view showing both toe sections completely connected to the body of the foot of the hose giving the appearance similar to any other hose.

Figure 4 is a sectional view on line 4—4 of Figure 3.

45 Referring to the drawings, 1 identifies the body of the foot of the hose, which is knitted on a circular or seamless machine. When the hose has been knitted to a point approximating a position substantially close to the 50 toe portion of the hose, that is a portion

adjacent where the toes of the foot may bend, the machine is stopped.

The extra toe sections may be made on a separate circular or seamless machine.

These extra toe sections constituting the 55 inner toe section 3 of the hose may then be transferred by means of a transfer bar to the seamless or circular machine which has knitted the body of the foot of the hose, then the machine continues in operation and 60 knits the outer and inner toe sections 2 and 3 to the hose. This operation of joining the two toe sections is simultaneously accomplished.

However, in making the inner and outer 65 toe sections up to this point, both toe sections are left free and unattached as identified at 4 for a distance substantially half the circumference of the body of the foot portion of the hose.

70 After the hose has been completed up to this point the hose is transferred from the circular or seamless machine to what is known, in the trade, as a looper, which operates to close both toe sections 2 and 3.

75 It is also to be understood that the second or inner toe section may be joined into the hose at any predetermined point. In closing the two toe sections are closed, the parts 5 and 6 are joined, which is accomplished on 80 a machine known in the trade as a looper.

In constructing hose with double toes, the 85 hose is knitted up to a point adjacent the ball of the foot, and an inner toe section 3 (which has been preknitted on a separate or another circular or seamless machine) is run on to the needles by means of a transfer bar, and at the same time the inner toe section is attached or knitted into the body of the foot of the hose the outer toe section is 90 knitted to the body of the foot of the hose. The outer toe section is then completed, but obviously as shown in Figure 1 at a point where the two sections are attached, the inner toe section being preknitted and the outer toe section subsequently knitted, portions of both toe sections are left free and unattached, and as previously stated these free and unattached parts 5 and 6 are subsequently joined on a machine known in the 100

trade as a looper, so that when the hose is complete it will appear as in Figures 3 and 4.

The invention having been set forth, what is claimed is:

- 5 In a process for knitting multiple toe hose on a circular machine, the steps consisting in knitting the hose to a line adjacent the toe portion thereof, running a pre-knitted toe section having the usual loopers rounds on 10 to the needles which are knitting the foot section, and then knitting an outer toe section over the inner toe section but separate therefrom, the initial starting knitting steps of the outer toe section being simultaneous 15 with the attaching of the inner toe section, knitting the outer toe section so that the loopers rounds thereof register with the loopers rounds of the inner toe section, leaving portions of both toe sections free and 20 unattached, and then finally closing the free and unattached portions by means of a looper.

In testimony whereof he affixes his signature.
